UNITED STATES PATENT OFFICE.

GEORGE L. WATERHOUSE, OF NEW YORK, N. Y.

APPARATUS FOR PUMPING LIQUID.

No. 811,110.

Specification of Letters Patent.

Patented Jan. 30, 1906.

Application filed June 13, 1905. Serial No. 264,984.

To all whom it may concern:

Be it known that I, GEORGE L. WATERHOUSE, a citizen of the United States, residing in New York city, borough of Manhattan, New York, have invented certain new and useful Improvements in Apparatus for Pumping Liquid, of which the following is a specification.

My invention relates to an improved method of and apparatus for pumping liquid by utilizing the direct displacing force of steam in conjunction with a vacuum caused by the condensation of the steam, and has for its object to utilize and conserve the heat absorbed by the surface of a body of liquid while being directly displaced by steam under pressure and for conserving pressure and heat contained in the displacing-steam for preheating the surface of another body of liquid to be pumped, and thereby starting a pressure thereon before live steam is admitted thereto, all to the end that heat which would otherwise be lost is conserved and, with the steam, used over again, thereby obtaining an increased degree of efficiency and economy in the use of steam when employed in operating steam and vacuum pumps.

In carrying out my invention steam is successively admitted to a plurality of receptacles and successively condensed in each to cause the same to be charged with liquid up to a substantially predetermined level, but at such a height as to leave a space in the receptacle above the liquid, and heated surface liquid and steam are successively forced into such space under pressure from one receptacle to another, whereby the upper interior of each receptacle is preheated and a pressure upon the surface of the liquid to be pumped is also thus started before live steam is admitted at a higher pressure.

In the apparatus shown in the accompanying drawings I provide a plurality of receptacles having liquid induction and eduction passages, pipes, and valves, a steam-pipe communicating with the upper interior of each receptacle and provided with valves, means made dependent upon the liquid being forced from each receptacle until its surface reaches a substantially predetermined low level above that of the main discharge for actuating the steam-valves to control the flow of steam to the receptacles to accord with the rise and fall of the surface of the liquid in each, means for admitting condensing liquid to the upper interior of each receptacle, and

transfer passages or pipes provided with suitable valves for directing heated surface liquid and steam from the lower interior of one receptacle after the main body of cooler liquid has been discharged therefrom into the upper interior of the other receptacle after the same has been properly charged with liquid and before the live steam is admitted to the latter.

In accordance with the foregoing a very small quantity of live steam is condensed while exerting pressure on the cooler liquid below for forcing the liquid through the discharge-passage. When the surface of the liquid in a receptacle reaches a substantially predetermined low level above the level of the main discharge, the steam is shut off by reason of the flow of liquid from the lower part of the receptacle to the steam-valve-operating devices, and the heated surface liquid and steam are suddenly discharged from the lower level of such receptacle into the upper interior of another receptacle, into which live steam is immediately thereafter admitted, and the operations are repeated in the second receptacle, and so on alternately or successively, according to the number of receptacles employed. In the meantime the remaining steam in the first-named receptacle is partly condensed by its pressure being reduced, owing to the passage of a large part of the steam into another receptacle. Then the remaining part of the steam is brought in contact with the cooler liquid which remains in the receptacle after being stripped of its heated surface, and then condensation is completed by a small spray of condensing liquid forced into the receptacle, whereby a vacuum is formed, which causes the receptacle to be recharged with liquid during the time that another receptacle is being discharged, and so on.

Reference is to be had to the accompanying drawings, forming part hereof, wherein—

Figure 1 is a partly-sectional elevation of an apparatus embodying my invention. Fig. 2 is a detail sectional view of part of one of the receptacles, showing means for controlling the flow of condensing liquid. Fig. 3 is a detail sectional view of a modified form of the valve details shown in Fig. 2. Fig. 4 is a sectional detail view of means shown in Fig. 1 for controlling the flow of steam and liquid for operating the steam-valves, and Fig. 5 is a side view of Fig. 4.

Similar numerals of reference indicate corresponding parts in the several views.

The numerals 1 1^a indicate closed recep-

tacles, each provided with liquid-induction valves 2, a common induction-passage 3, liquid-eduction valves 4, and a common eduction-passage 5, all of which may be of any 5 well-known construction used in this class of pumps.

At 6 is indicated a steam-supply pipe, shown provided with branches 7 7^a, leading to steam-valves 8 8^a, communicating 10 with the upper interior of the receptacles 1 1^a.

At 9 is a cylinder having a movable member or piston 9^a and a piston-rod 9^b, passing through stuffing-boxes at both ends of the 15 cylinder, adapted to alternately engage the stems 8^b of the movable valve members 8^c of the steam-valves 8 8^a. At each extreme movement of the piston 9^a its rod 9^b opens one of the steam-valves 8 or 8^a by pushing in 20 the stem 8^b, admitting live steam to one of the receptacles so long as the piston remains at that end of its stroke; but as soon as the piston 9^a begins to move in the opposite direction and the rod 9^b first withdraws from 25 the adjacent valve-stem 8^b then the corresponding valve closes by the steam-pressure acting upon the part 8^c, thereby shutting off steam from such receptacle. The distance between extreme ends of the piston-rod 9^b is 30 less than the distance between the valve-stems 8^b, so that for a space of time during the travel of the piston both steam-valves may be closed. By this means each of the 35 steam-valves one at a time is opened and held open, while the piston reaches and remains at the extremes of its motion, and both of the valves are closed while the piston is under motion or on its way between the extremes of its movements, and during which 40 latter time heated surface liquid and steam is to be transferred from one receptacle to the other.

The means I have shown for causing the heated surface liquid and steam to be transferred alternately from one of two receptacles 45 to the other are as follows: At 11 11^a are pipes leading from the lower interior of the receptacles and provided with check-valves 11^b, said pipes being shown connected with a common pipe 12, that leads to the transfer-valve case or chamber 10, that communicates with the upper interior of the receptacles 1 1^a, as 50 by pipes 13 13^a, provided with check-valves 13^b, opening only toward the corresponding receptacle. At 10^c is shown a double-ended valve within casing 10, adapted to close against the seats 10^d 10^e to control the passage of liquid through the pipes 13 13^a to the respective receptacles, and said valve is arranged 55 to be operated by and coincidentally with the operations of piston 9^a. For this purpose I have shown a carrier or arm 9^c connected with piston-rod 9^b and having a connecting-rod 9^d, leading to a rocker-arm 60 10^a, which enters the transfer-case 10, as

through a stuffing-box, (not shown,) the inner end 10^b of the rocker-arm being movably or pivotally connected with the valve 10^c. By the arrangement shown the valve 10^c is reciprocated by the connection between it 70 and the piston 9^a, so that said valve 10^c moves in an opposite direction to the piston 9^a, but reaches the extremes of its oscillating motions to alternately close the valve-seats 10^d 10^e at about the same time that the piston 9^a reaches the extremes of its linear movements. The arrangements above described are such that the check-valves 11^b open only in reverse directions or in such manner that no passage is open through 75 them between the lower parts of the receptacles; but the flow can be only from both valves through pipe 12, and similar conditions are present with respect to valves 13^b in that the flow can only be from pipe 12 80 through said valves to the receptacles and not between the upper parts of the receptacles; but a passage is thus provided from the lower interior of said receptacles 1 1^a through the transfer-pipe 12 and valve-casing 10 to 85 the upper interior of both receptacles, and the passage from the lower interior of each receptacle to the upper interior of the other is controlled as follows: When piston 9^a moves to the extreme left of its motion, its 90 rod 9^b strikes the adjacent valve-stem 8^b, opens valve 8^c, and admits steam to receptacle 1, the check-valve 13^b preventing the flow of such steam to casing 10, while at the same time the movement of piston 9^a has 95 carried the transfer-valve 10^c to the opposite extreme of its motion and closed against the seat 10^e to prevent the flow of liquid from receptacle 1 to receptacle 1^a while the parts are 100 in such positions. Then steam in receptacle 1 causes a pressure therein; but this pressure cannot force liquid through check-valves 11^b into the lower part of receptacle 1^a nor past valve 10^c and seat 10^e into the upper interior of receptacle 1^a, (because valve 10^c has closed the passage 10^e,) nor can such 105 pressure pass through the pipe 13 past its check-valve 13^b because its own pressure in receptacle 1 bars its return. Therefore the pressure is now confined in receptacle 1 and 110 used to displace the liquid therein and force it out through the discharge-passage 5.

The means shown for shifting piston 9^a to operate the steam-valves 8 8^a and the valve 10^c for respectively controlling the flow of 115 steam to the receptacles and the flow of heated surface liquid and steam from one receptacle to the other are as follows: Similar devices being arranged in each receptacle, pipes 14^d connect with opposite ends of cylinder 9 and lead into the lower portion of the receptacles 1 1^a, which pipes near the lower portions of the receptacles are provided with valves 14^e, having means, such as floats 14, 120 for operating them. The valves 14^e I have 130

shown are in the nature of three-way valves of such construction that they will open a passage from the receptacles, preferably through the screens 14^a and check-valve casings 14^b through pipes 14^d to opposite ends of cylinder 9. Pipes 14^e communicate with valves 14^c and lead to the atmosphere, being shown passing through the bottom of the receptacles. The details of valves 14^c, &c., are shown in Figs. 4 and 5, and the arrangement is such that when float 14 is elevated a free passage is provided from pipe 14^d to pipe 14^e, leading to the open air; but when the float 14 is down the passage to pipe 14^e is closed and a passage then opened from the lower interior of the receptacle through the screen 14^a and up pipe 14^m, past check-valve 14^b and valve 14^c, and thence up pipe 14^d to the cylinder 9. In this valve the blade 14^f moves the valve member 14^g, the rod 14^h being connected to the blade 14^f. The check-valve 14^b prevents air from being sucked into the receptacle through pipe 14^e when float 14 is down, and a vacuum is formed in the receptacle. When the surface of the liquid in the receptacle lowers so that it falls below the float 14, the float descends and opens valve 14^c, thus providing direct communication between the lower interior of the receptacle through 14^m and 14^d to cylinder 9, whereby the steam-pressure in the receptacle will force liquid into cylinder 9 and move piston 9^a, as to the right in Fig. 1, thus permitting the steam-valve 8^c to close and shut off steam from the receptacle, as 1, and the first of the same movement of the piston 9^a will act upon the transfer-valve 10^c by withdrawing it from the valve-seated aperture 10^e, thus immediately opening a passage for the heated surface liquid and steam to pass from the lower interior of one receptacle, as 1, through pipe 12, casing 10, and pipe 13^a into the upper interior of the other receptacle, and this flow continues while the piston 9^a is under motion, as to the right in Fig. 1, and until it opens the steam-valve 8^c on the right and admits steam to receptacle 1^a. By this time the heated fluid in the form of heated surface liquid and steam from receptacle 1 has preheated the upper interior of receptacle 1^a and also the surface of its liquid, besides starting a pressure upon the same, so that when live steam enters this receptacle the causes which would otherwise produce its wasteful condensation are removed and its work of displacing liquid can be economically performed. As soon, however, as the heated surface liquid and steam is discharged from one of the receptacles, as 1, condensation of the remaining steam rapidly begins, owing to the removal of the heated surface liquid, and this condensation is completed, owing to the higher pressure caused by the admission of live steam in receptacle 1^a, which causes a limited flow of condensing liquid from recep-

tacle 1^a into the upper interior of receptacle 1 through the condensing-pipe 15 and its check-valve 16, connecting the upper interior of receptacle 1 with pipe 12, (a similar pipe 15^a and check-valve 16^a connecting pipe 12 with the upper interior of receptacle 1^a,) and this inflowing condensing liquid completes the condensation of the steam in receptacle 1, producing a vacuum therein, which causes the receptacle to refill with liquid through its induction-pipe 3 and valve 2. While in Fig. 1 the arrangement is such that condensing liquid will flow into a receptacle through its pipe 15 or 15^a upon live steam entering one receptacle after pressure 80 in the other receptacle has been reduced, I have shown in Fig. 2 means for checking the inflow of condensing liquid upon the liquid in the receptacle reaching a substantially predetermined high level. In Fig. 2 the condensing-pipe 15 is provided with a spraying tube or nozzle 15^b and a valve 17, provided with a float 17^a, connected with the cam or operating part 17^c of the valve which is adapted to press on the stem 17^d of the check-valve 17^e to hold the latter upon its seat. In the arrangement shown the rod 17^b is bent substantially at a right angle to the plane upon which the float is caused to rise and fall in following the surface of the liquid 95 in the receptacle, and the relation of the cam 17^c to the stem 17^d is such that when the float 17^a is down the valve 17^e can rise, but when the liquid rises in the receptacle to a substantially predetermined height the rising 100 of the float 17^a will cause cam 17^c to hold valve 17^e firmly upon its seat, so that no more liquid can enter the receptacle through pipe 15 after the surface of the liquid rises therein to a substantially fixed level. By 105 this means the entrance into the receptacle of condensing liquid maintains a vacuum in the receptacle capable of charging the receptacle with liquid up to a substantially predetermined high level, and then as the flow of condensing liquid into the receptacle is stopped by the valve the vacuum is broken by steam generated from the surface of the charging liquid caused by its contact with and absorbing the heat from the metal of the receptacle 110 upon the liquid rising a slight distance therein above the level it had obtained when the condensing liquid was shut off, thereby leaving a space in the upper interior of each receptacle above that occupied by the discharging liquid into which space heated surface liquid and steam can be forced from the other receptacle for preheating the same preparatory to the admission of live steam thereto. Devices similar to that shown in Fig. 2 will 115 be used in both receptacles.

Fig. 3 shows at right angles the valve and float of Fig. 2 slightly modified. In this case the rod 17^b extends substantially at right angles to the axis 17^f of the cam or finger 17^c, 120

so that when the float 17^a is down cam 17^e releases the stem 17^d and permits check-valve 17^e to rise to admit condensing liquid to the receptacle, and when the float rises to a substantially predetermined high level by the liquid charged into the receptacle the cam 5 will hold the valve 17^e closed.

The complete method of pumping liquid and the operation of the parts set forth according to my invention may be described as follows: Assuming that receptacle 1^a is charged with liquid up to a substantially predetermined high level, (at or slightly above the discharge-opening of pipe 15^a into the receptacle,) that piston 9^a is at the left, valve 8^c at the right, closed, valve 10^c closed against the seat 10^e, and live steam thereby having been admitted to receptacle 1 to discharge liquid therefrom through outlet 5, 10 then the surface of the liquid in receptacle 1 having reached the float 14 the latter will descend, as in Fig. 1, and will open a passage through pipes 14^m and 14^d into cylinder 9, causing liquid in the receptacle, as from the 15 lower part thereof, to push piston 9^a to the right, whereupon rod 9^b will pass away from rod 8^b and valve 8^c at the left will close to shut off inflowing steam from receptacle 1 and simultaneously valve 10^c will move to the left 20 and open a passage through pipe 13^a, (valve 8^c at the right during this time remaining closed,) and the heated surface liquid and steam from receptacle 1 will pass from the lower interior thereof through pipes 11 and 12 and casing 25 10 past check-valve 13^b and through pipe 13^a into receptacle 1^a, whereby this heated liquid and steam preheats the upper interior of receptacle 1^a and also the surface of its contained liquid and will start a pressure upon 30 the same. This flow of heated liquid and steam from receptacle 1 continues while piston 9^a is under motion to the right (caused by pressure of the liquid from receptacle 1 in pipe 14^d) until the piston 9^a causes valve 8^c 35 at the right to open and valve 10^c to close against seat 10^e, whereupon live steam will be admitted to receptacle 1^a. Upon the steam-valve 8^c of receptacle 1 closing, as stated above, condensation of steam in said 40 receptacle starts and the pressure therein lowers, and when the live steam enters receptacle 1^a liquid flows therefrom through pipes 11^a 12 and pipe 15 into receptacle 1, condensing the steam and creating a vacuum 45 therein, whereby said receptacle will be charged with liquid, and as the liquid rises in said receptacle float 14 will rise, closing the passage from pipe 14^m to 14^d (the check-valve 14^b preventing suction of air into the receptacle through pipe 14^m) and opening a passage from 14^d to 14^e, as shown in Fig. 4, to permit the discharge of liquid from cylinder 9 during the return movement of piston 9^a. During the time that receptacle 1 is being 55 charged with liquid the live steam in receptacle

1^a causes the liquid to be discharged therefrom through outlet 5, and when the liquid in receptacle 1^a falls so that its float 14 descends and opens communication between its pipes 14^m and 14^d liquid from the lower 70 part of receptacle 1^a will be forced through said pipes to push piston 9^a to the left in Fig. 1, whereupon steam-valve 8^c of receptacle 1^a will close, valve 10^c will move from seat 10^e, hot surface liquid and steam from receptacle 75 1^a will pass through pipes 12 and 13 into receptacle 1, preheating the upper interior of the same and the surface of the liquid therein, (in manner described with respect to receptacle 1^a,) and the movement of piston 9^a to 80 the left will force the liquid out of cylinder 9 through pipes 14^d and 14^e and the operations above described will be repeated. It will thus be understood that the charging of the receptacles with liquid, passing heated surface liquid and steam from the lower interior of one receptacle to the upper interior of the other receptacle for preheating the latter and the surface of the contained liquid, admitting live steam upon the preheated surface of a 85 charge of liquid, and passing condensing liquid from one receptacle to another take place alternately, whereby the operations are maintained continuously while steam is supplied through pipe 6. 95

Heretofore steam and vacuum pumps with which I am familiar have depended upon admitting air into the receptacle or receptacles to form an insulating stratum between the steam and the liquid therein, which air the 100 steam displaced, and in some cases the discharge of air from the receptacle has been utilized for aiding condensation of the steam and also for actuating the valves which control the flow of steam to the receptacle or receptacles. In my invention air is not depended upon as an essential element in carrying out the invention, as the cold liquid drawn into the receptacle is covered by a stratum of the same liquid heated by its contact with the heated metal of the receptacle in which it rises and again is covered by heated surface liquid and steam discharged upon its surface from another receptacle, whereby the upper interior of the receptacle 110 is preheated before live steam is admitted thereto, and instead of utilizing the discharge of air from the receptacle for actuating the steam controlling valve or valves I use other fluid for such purpose. 120

My invention is not limited to the details of construction shown and described, as they may be varied without departing from the spirit thereof. Furthermore, while I have illustrated and described two receptacles associated together it will be understood that any desired number of receptacles may be associated and connected together by means which will permit the operations and results above set forth to take place. 130

Having now described my invention, what I claim is—

1. An apparatus of the character described comprising a plurality of receptacles provided with liquid induction and eduction means, means for controlling the flow of steam to each receptacle to accord with the rise and fall of liquid therein, means for discharging heated fluid from the lower interior 10 of one receptacle into the upper interior of another receptacle upon a charge of liquid therein before steam is admitted thereto, and means for causing condensation of steam in said receptacles after liquid has been discharged therefrom, substantially as described.
2. An apparatus of the character described comprising a plurality of receptacles provided with liquid induction and eduction means, means for controlling the flow of steam to each receptacle to accord with the rise and fall of liquid therein, means for discharging heated fluid from the lower interior 20 of one receptacle into the upper interior of another receptacle upon a charge of liquid therein before steam is admitted thereto, and means for causing the flow of condensing fluid from one receptacle into the other after liquid has been discharged from the latter, substantially as described.
3. An apparatus of the character described comprising two receptacles provided with liquid induction and eduction means, means for controlling the flow of steam to each receptacle to accord with the rise and fall of liquid therein, means for discharging heated fluid from the lower interior of one receptacle into the upper interior of the other receptacle upon a charge of liquid therein before steam is admitted thereto, means for causing the 30 flow of condensing fluid from one receptacle into the other after liquid has been discharged from the latter, and means for stopping the flow of condensing liquid to each receptacle after it has been charged with liquid 40 to a substantially predetermined high level therein, substantially as described.
4. An apparatus of the character described comprising a plurality of receptacles provided with liquid induction and eduction means, means for alternately admitting steam to and shutting it off from each receptacle, means for discharging heated liquid from the lower interior of each receptacle to the upper interior of another receptacle before live steam is admitted thereto, means for condensing the 50 steam in each receptacle, and means for preventing the rise of liquid in each receptacle above a substantially predetermined high level therein, substantially as described.
5. A pumping apparatus comprising a pair of receptacles provided with liquid induction and eduction means, means to alternately admit steam to each receptacle, means to alternately discharge heated surface liquid and 60 steam from each receptacle to the other while live steam is shut off from the receptacle receiving such heated surface liquid, and means to alternately cause condensation of steam in said receptacles, substantially as described.
6. A pumping apparatus comprising a pair 70 of receptacles provided with liquid induction and eduction means, valves to admit steam to said receptacles, means to open said valves alternately and leave both valves closed for a period of time, passages connecting the lower 75 interior of each receptacle with the upper interior of the other receptacle, means to control the flow of fluid through said passages and to open the passage from one receptacle to another while steam is shut off from both 80 receptacles, substantially as described.
7. A pumping apparatus comprising a pair of receptacles provided with liquid induction and eduction means, valves to admit steam to said receptacles, means to open said valves 85 alternately and leave both valves closed for a period of time, passages connecting the lower interior of each receptacle with the upper interior of the other receptacle, means to control the flow of fluid through said passages 90 comprising devices to open the passage from one receptacle to another while steam is shut off from both receptacles and to close the passage into one receptacle while live steam is entering the other receptacle, and means for 95 condensing liquid in said receptacles; substantially as described.
8. A pumping apparatus comprising a pair of receptacles provided with liquid induction and eduction means, valves for admitting 100 steam to said receptacles, means to alternately operate said valves and leave them both closed for a period of time, a passage connecting the lower interior of each receptacle with the upper interior of the other receptacle 105 and provided with valves to prevent the return flow from one receptacle to the other, and a valve device to control the flow of fluid through said passage to each receptacle arranged to open the passage from one receptacle to the other while live steam is shut off from the last-named receptacle, the steam-valve-operating means serving to admit steam to the last-named receptacle after heated fluid from the other receptacle has entered the same, substantially as described. 110
9. A pumping apparatus comprising a pair of receptacles provided with liquid induction and eduction means, valves to admit steam to said receptacles, passages connecting the 120 lower interior of each receptacle with the upper interior of the other receptacle, valves to prevent the return flow through said passages from one receptacle to the other, a valve device to control the flow of heated fluid 125 through said passages from one receptacle to the other, mechanism for operating the steam-valves connected with said valve device for operating the latter, and means for causing said mechanism to operate to alternately 130

control the flow of steam to said receptacles to accord with the rise and fall of liquid therein; substantially as described.

10. An apparatus of the character described comprising a plurality of receptacles provided with liquid induction and eduction means, means for controlling the flow of steam to each receptacle, means for discharging heated fluid from the interior of one receptacle into the interior of another receptacle

upon a charge of liquid therein before steam is admitted thereto, and means for causing condensation of steam in said receptacles after liquid has been discharged therefrom, substantially as described.
